(57) **CLAIM**

The ornamental design for a knob for vacuum cleaner, as shown and described.

DESCRIPTION

FIG. 1 is a perspective view of a knob for vacuum cleaner, showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is another perspective view thereof shown in an environment of use.

The broken lines illustrating portions of the knob for vacuum cleaner form no part of the claimed design.

1 Claim, 8 Drawing Sheets
